R. L. WILCOX

CLEARING MECHANISM

Filed Feb. 6, 1922

Inventor
Richard Lester Wiley
By George H. Hall
Atty

UNITED STATES PATENT OFFICE.

RICHARD LESTER WILCOX, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT.

CLEARING MECHANISM.

Application filed February 6, 1922. Serial No. 534,542.

To all whom it may concern:

Be it known that I, RICHARD LESTER WILCOX, a citizen of the United States, residing at Waterbury, in the county of New Haven and State of Connecticut, have invented certain new and useful Improvements in Clearing Mechanisms, of which the following is a specification, reference being had therein to the accompanying drawings.

10 This invention relates to new and improved clearing mechanism, referring more particularly to mechanisms for clearing the entrance end of a chute leading from a hopper, by stripping therefrom all blanks 15 not correctly positioned therein.

It is the object of this invention, among other things, to provide a device for this purpose, wherein only readily substituted portions thereof require changing to accommodate blanks of varying sizes, the primary 20 portions remaining engaged and unaltered.

The improvements in the details and arrangement of parts will be apparent from an inspection of the accompanying drawings 25 in connection with the description hereinafter contained and wherein a preferred embodiment of the invention is disclosed for the purpose of imparting an understanding thereof.

30 Referring to the drawings in which like characters of reference designate like parts in the several figures;

Figure 1 is an elevation of my improved device with that portion of the hopper and discharge chute immediately adjacent thereto;

Figure 2 is a plan view thereof;

Figure 3 is a sectional view, taken generally upon line 3—3 of Figure 1; and

40 Figure 4 is an enlarged sectional elevation, taken generally upon line 4—4 of Figure 1.

Heretofore clearing mechanisms have usually been arranged for an extremely limited 45 range of sizes of blanks and to accommodate even this narrow field required substitution which might be termed the primary portions of the mechanism. This demands an almost unlimited supply of parts that 50 are costly to make and are more or less complicated in their means and method of assembly and therefore not entirely practical, and at the best do not meet the requirements.

My device may be used in connection with 55 blanks of an almost unlimited range of sizes, etc. by the mere substitution of a member that is of an extremely simple construction and inexpensive to make and the primary parts of the mechanism are not changed or 60 disturbed.

In the drawings, 10 designates a portion of a hopper which may be of any desired form, 11 the chute plates leading therefrom, as is usual, with an open space 12 therebetween, 13 the cover that is held in any preferred manner above the said opening 12 with an open space between it and the plates 11, sufficient to permit the head of the blank 14 to pass thereunder as shown in Figure 4. 70

All of the parts above described are of a well known form and structure.

Fixed in a portion of the hopper 10 is a stud 15 upon which is rotatably mounted a sheave pulley 16 having a cam 17 upon one 75 end of the hub thereof. A nut 18 and collar 19 prevent axial movement of the sheave pulley upon the stud 15.

On the shaft 20 is a rock lever 21 having a cam arm 22 forming part thereof upon the 80 outer end of which is a lug 23 which is engaged by the cam 17 during a portion of its rotation, and an arm 24 which projects toward the chute plates 11. Near the lower inner end of the arm 24 a stripper plate 25 85 is secured by screws 26 or other similar means. In the end of this latter plate is a slot 27, that is slightly larger than the diameter of the head of the blank 14 and projecting therefrom is a second slot 28 of sufficient size to pass freely over the cover 13. 90

In the arm 24 is a slot 29 which registers with the slot 28 in the stripper plate, its length being sufficient to accommodate a slot 28 of the maximum length. 95

The rock lever 21 is moved in one direction by the cam 17 and as the high point 38 thereof approaches the lug 23 on the cam arm 22, the rock lever 21 swings so that the stripper plate 25 is moved toward the 100 right in Figure 1, that is, away from the upper or inner end of the cover 13. After said high point has passed under the lug 23, the rock lever is moved in the reverse direction by a plunger 30 actuated by the spring 105 31 and the stripper plate 25 sweeps over the top of the chute plates 11, snapping or kicking all blanks off the top thereof, which

are not in proper position thereon. That is, all blanks which are not so arranged relatively to the chute that the shanks thereof are in the open space 12 between the chute plates 11 and the head resting upon the tops thereof, substantially shown in Figure 4, which blanks when so aligned pass through the slot 27 in the plate 25 and travel down the chute to the discharge point.

16 To relieve the shock upon the rock lever 21 and also to eliminate the noise or click thereof there has been inserted a stud 32 in the hopper 10 which projects into an opening 33 in the cam arm 22 against which 15 strikes a resilient plug 34 in the cam arm when the latter is in its down position. The position of the stud and plug being such that the lug 23 when in its down position does not contact with the lowest point 20 of the periphery of the cam 17, as shown in Figure 1. The driver will function correctly however even if the lug 23 did bring up against the cam 17.

17 The plate 25 may be used for blanks that 23 vary slightly in their dimensions, but is readily replaced by other plates having slots therein of the proper size to accommodate blanks whose dimensions vary greatly therefrom.

30 A guide plate 35 of the usual form, with an angular face 36 thereon, is connected with the hopper to guide the blanks toward the top of the chute plates 11 when the same are thrown against the side plate 37.

35 With this construction all of the primary portions of the mechanism are not changed or altered, the wide range of sizes of blanks being accommodated by merely substituting a plate 25 slotted to suit, that is inexpensive 40 to make and requires little or no skill to assemble.

45 The sudden snap or kick given to the improperly aligned blanks by the plate 25 is very effectual in keeping the entrance to the discharge chute clear and thus prevents clogging thereof, the blanks receiving a sufficient blow to generally return them to the hopper.

50 Minor changes and alterations may be made within my invention, aside from those herein suggested, and I would therefore have it understood that I do not limit myself to the exact construction herein shown and described, but claim all that falls fairly 55 within the spirit and scope of the appended claims.

What I claim as new and desire to secure by Letters Patent, is:

60 1. In combination with a feed chute, of means for stripping therefrom all blanks which are not in regular processional line therein, comprising a rock member pivotally mounted upon a fixed part, a member connected and movable therewith, having a recess therein slightly larger than the head

of the blank, and means for actuating said rock member whereby the movement of the end thereof that is adjacent to the blanks is unrestrained when traveling against the path of movement of the blanks and controlled while moving in the opposite direction. 70

2. In combination with a feed chute, of means for stripping therefrom all blanks which are not in regular processional line 75 therein, comprising a rock member pivotally mounted upon a fixed part, means for actuating the same whereby the movement of the end thereof that is adjacent to the blanks is unrestrained when traveling against the path of movement of the blanks and controlled while moving in the opposite direction, and an element connected and movable with said rock member that projects over the head of the blanks and during its movement swings over the top of said chute. 80

3. In combination with a feed chute, of means for stripping therefrom all blanks which are not in regular processional line 90 therein, comprising a rock member pivotally mounted upon a fixed part, means for actuating the same whereby the movement of the end thereof that is adjacent to the blanks is unrestrained when traveling against the path of movement of the blanks and controlled while moving in the opposite direction, an element connected and movable with said rock member that projects over the head of the blanks and during its movement 95 swings over the top of said chute, positive means for actuating said rock member in one direction, and yielding means for actuating the same in the opposite direction. 100

4. In combination with a feed chute, of means for stripping therefrom all blanks which are not in regular processional line 105 therein, comprising a rock member pivotally mounted upon a fixed part, means for actuating the same whereby the movement of the end thereof that is adjacent to the blanks is unrestrained when traveling against the path of movement of the blanks and controlled while moving in the opposite direction, an element connected and movable with said rock member that projects over the head of the blanks and during its movement 110 swings over the top of said chute, positive means for actuating said rock member when the said element connected therewith is moving over said chute in a path substantially parallel to the direction of movement of the blank therein, and yielding means for moving the same in the opposite direction. 115

5. In combination with a feed chute, of a 120 cover therefor, means for stripping from said feed chute all blanks that are not in regular processional line therein, comprising a rock member pivotally mounted upon a fixed part having a slot therein that reg- 125

isters with said cover, a plate slotted so as to pass over said cover and the head of the blanks when in said regular processional line, and means for actuating said rock member so that said plate will swing over the top of said chute.

6. In combination with a feed chute, of means for stripping therefrom all blanks which are not in regular processional line 10 therein, comprising a rock member pivotally mounted upon a fixed part, an element connected and movable with said rock member that projects over the head of the blanks and during its movement swings 15 over the top of said chute, and a cam for actuating said rock member when the end thereof adjacent to the blanks is moving with the blanks.

7. In combination with a feed chute, of 20 means for stripping therefrom all blanks which are not in regular processional line therein, comprising a rock member pivotally mounted upon a fixed part, an element connected and movable with said rock member that projects over the head of the blanks and during its movement swings 25 over the top of said chute, and a cam actuating said rock member when the end thereof adjacent to the blanks is moving 30 with the blanks, and yielding means for actuating it in the opposite direction.

8. In combination with a feed chute, of 35 means for stripping therefrom all blanks which are not in regular processional line therein, comprising a rock member pivotally mounted upon a fixed part, an element connected and movable with said rock member that projects over the head of the blanks and during its movement swings 40 over the top of said chute, a cam for actuating said rock member in one direction, and a spring actuated plunger for actuating the same in the opposite direction.

9. In combination with a feed chute, of

means for stripping therefrom all blanks 45 which are not in regular processional line therein, comprising a rock member, an element separably connected with said rock member that projects over the head of the blanks and during its movement swings 50 over the top of said chute, a cam for actuating said rock member in one direction, and a spring actuated plunger for actuating the same in the opposite direction, and means for limiting the movement of said 55 rock member in one direction so as to hold it out of engagement with said cam during a portion of the movement thereof.

10. In combination with a feed chute, of means for stripping therefrom all blanks 60 which are not in regular processional line therein, comprising a rock member pivotally mounted upon a fixed part having a cam arm thereon, a second arm thereon, a member connected with the second arm and 65 movable therewith, said member being slotted so as to pass over the head of the blanks in said chute, a cam during its rotation having contact with said cam arm, and a plunger for moving said cam arm toward 70 said cam.

11. In combination with a feed chute, of means for stripping therefrom all blanks which are not in regular processional line therein, comprising a rock member having 75 a cam arm thereon, a second arm thereon, a member separably secured to the second arm and slotted so as to pass over the head of the blanks in said chute, a cam during its rotation having contact with said cam 80 arm, a plunger for moving said cam arm toward said cam, and means for limiting the movement of said rock member when actuated by said plunger.

In testimony whereof, I have hereunto 85 affixed my signature.

RICHARD LESTER WILCOX.
